(57) **CLAIM**

We claim the ornamental design for a headband for head-mounted display, as shown and described.

DESCRIPTION

FIG. 1 is a front perspective view of a headband for head-mounted display showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view thereof shown with a first example head-mounted display attached;

FIG. 9 is a front perspective view thereof shown with a second example head-mounted display attached;

FIG. 10 is a right-side view thereof shown with a third example head-mounted display attached in a first position;

FIG. 11 is a right-side view thereof shown with a fourth example head-mounted display attached in a second position;

FIG. 12 is a right-side view thereof shown with a fifth example head-mounted display attached in a third position;

FIG. 13 is an enlarged view of the portion encircled in FIG. 1;

FIG. 14 is an enlarged view of the portion encircled in FIG. 2;

FIG. 15 is an enlarged view of the portion encircled in FIG. 3;

FIG. 16 is an enlarged view of the portion encircled in FIG. 4;

FIG. 17 is an enlarged view of the portion encircled in FIG. 6;

FIG. 18 is an enlarged view of the portion encircled in FIG. 7;

FIG. 19 is an enlarged view of the portion encircled in FIG. 9; and,

FIG. 20 is an enlarged view of the portion encircled in FIG. 12.

The broken lines in the figures depict portions of the headband for head-mounted display which form no part of the claimed design. The broken lines in FIGS. 8 through 12, (Continued)

19 and **20** which depict the example head-mounted display are for environmental purposes only, and form no part of the claimed design.

The dot-dash broken lines encircling portions of the claimed design that are illustrated in enlargements form no part of the claimed design.
